CORPORATION OF MAINE

ART OF CRACKING HYDROCARBONS

Application filed July 12, 1929. Serial No. 377,815.

This invention relates to improvements in the manufacture of lower boiling hydrocarbon oils, such as gasoline, from higher boiling hydrocarbon oils, such as gas oil. The invention will be described in connection with the accompanying drawings which illustrate, diagrammatically and conventionally, apparatus embodying and for carrying out the invention. In the accompanying drawings, Fig. 1 represents, in elevation and partly in section and with parts broken away, apparatus embodying and adapted for carrying out the invention and Fig. 2 is a fragmentary section through and just above the lower ends of the heating tubes illustrated in Fig. 1.

Referring to the drawings, a stream of high boiling oil is forced, by means of pump 2, through a battery of series connected banks of series connected vertical heating tubes arranged in a heating flue in heating furnace 1 into the vapor separating receptacle 3 from which vapors including vapors of the desired low boiling oil are taken off, the oil being heated to a cracking temperature during passage through the heating tubes. The battery of heating tubes consists, as just mentioned, of a plurality of series connected banks 11, 12, 13, 14, 15, 16, 17 and 18 of heating tubes each of which banks consists of a plurality of series connected heating tubes. These several banks of heating tubes are arranged transversely to the general direction of flow of the heating gases through the heating flue. The heating gases enter the upper end of the heating flue through passage 4 from the firebox 5 in which fuel is burned for supplying heat to the operation and pass in alternating down and up and down flow through the heating flue to the stack flue 6. The oil flowing through the series connected banks of heating tubes flows successively upwardly and downwardly, in alternating flow, through the series connected heating tubes forming the several banks. The alternations in flow of the heating gases are substantially less in number than the alternations in flow of the stream of oil flowing through the banks of heating tubes; that is the oil flow alternates several times between each alternation in flow of the heating gases. The oil sup-

plied to the battery of heating tubes, through connections 7, flows first through bank 18, then through bank 17, then through bank 16 and so on, until discharged from bank 11 through connection 8. The flow of heating gases through the heating flue in which the heating tubes are arranged is directed, as just described, by means of the baffles 9 and 10.

The vapors taken off from the vapor separating receptacle 3, through connection 19, are subjected to a refluxing operation in reflux tower 20 from which the vapors remaining uncondensed escape through connection 21 to the condenser 22 arranged to discharge into the receiver 23 from which a condensed distillate product is discharged through connection 24 and uncondensed vapors and gases through connection 25. Pressure in the vapor separating receptacle 3 may be maintained and regulated by means of valve 26, or by means of suitable valves arranged beyond the condenser or receiver. Raw oil is supplied to the refluxing operation through connection 27 by means of pump 28, and utilized therein as a direct refluxing medium for effecting and controlling the operation. Admixed reflux condensate and raw oil are supplied to the battery of heating tubes arranged in the heating furnace 1 from the refluxing operation through connections 29, 30 and 8 by means of pump 2. Residual oil is discharged from the vapor separating receptacle 3 through connection 31.

In initiating operation, oil is circulated from the vapor separating receptacle 3, by means of valved connection 32, through the battery of heating tubes and back to the vapor separating receptacle until normal operating conditions are reached, the valve in connection 32 being closed during normal operation. Connection 33, communicating through valved branches with the lower ends of each of the heating tubes, is provided for pumping out the battery of heating tubes at the end of a run. The initial charge of oil, at the beginning of a run, is supplied through connection 34, and the vapor separating receptacle 3 is pumped out at the end of a run through connections 32, 30 and 34. Additional raw oil, in addition to that supplied

through connection 27, may be supplied through connection 34 during operation. In carrying out the invention in the apparatus illustrated, vapors may be taken off from the vapor separating receptacle 3 under a pressure in the general range of 100-300 pounds per square inch, for example, and the oil forced through the battery of heating tubes may be heated therein to a temperature approximating 825-875° F. as discharged through connection 8 into the vapor separating receptacle 3, for example. The rate at which raw oil is supplied through connection 27 may be regulated to condense in the refluxing operation all constituents higher boiling than suitable as components of the desired distillate product, and residual oil may be discharged through connection 31 at a rate regulated to maintain a uniform liquid level in the vapor separating receptacle 3.

Instead of taking off vapors from the vapor separating receptacle 3 under substantial superatmospheric pressure, vapors may be taken off from the vapor separating receptacle 3 under a pressure in the general range of 1-10 pounds per square inch or under a somewhat higher pressure, for example, and the oil forced through the battery of heating tubes may be heated therein to a temperature approximating 850-925° F., as discharged therefrom, under a pressure in the general range of 300-600 pounds per square inch, for example, this pressure being regulated and released by means of the valve 35.

In the apparatus illustrated, the vapor separating receptacle 3, the reflux tower 20, and connections 8, 19, 29, 30 and 7 are with advantage thoroughly lagged or thermally insulated.

The heating furnace 1 may, with advantage, be arranged and operated as described in Letters Patent Nos. 1,574,546 and 1,574,547, issued to Sinclair Refining Company, February 23, 1926, on application of the late John E. Bell or as described in Letters Patent No. 1,623,773, issued to Sinclair Refining Company, April 5, 1927, on application of the late John E. Bell.

While the invention has been described more particularly as applied in conjunction with pressure distillation, or so-called "pressure shell", cracking operations, in connection with which it is of special value, it is also useful as applied in conjunction with operations in which high boiling oil is heated to a cracking temperature under high pressure and in which the hot oil products of this heating operation are separated into a vaporized fraction and an unvaporized fraction under lower pressure, or so-called "pressure coil" cracking operations.

We claim:

In the manufacture of lower boiling hydrocarbon oils from higher boiling hydrocarbon oils, the improvement which comprises forc-

ing a stream of high boiling oil through a battery of series-connected banks of series-connected vertical heating tubes arranged in a heating flue into a vapor separating receptacle, passing heating gases from a firebox in which fuel is burned for supplying heat to the operation in alternating down and up flow through said heating flue in a direction generally transverse to said banks of heating tubes, these alternations in flow of the heating gases being however substantially less in number than the alternations in flow of the stream of oil flowing through said series-connected banks of series-connected heating tubes, thereby heating the oil to a cracking temperature, and taking off vapors including vapors of the desired low boiling oil from said vapor separating receptacle.

In testimony whereof we affix our signatures.

EDWARD W. ISOM.
EUGENE C. HERTHEL.
